(57) **CLAIM**

I claim the ornamental design for a garment caddy, as shown and described.

DESCRIPTION

FIG. 1 is a perspective view of a garment caddy according to my new design;

FIG. 2 is a front elevational view thereof;

FIG. 3 is a rear elevational view thereof;

FIG. 4 is an elevational end view of a first end thereof;

FIG. 5 is an elevational end view of a second end thereof;

FIG. 6 is a top plan view thereof; and,

FIG. 7 is a bottom plan view thereof.

The broken or dashed lines in the drawing figures are for illustrative purposes only and form no part of the claimed design.
